UNITED STATES PATENT OFFICE.

JAMES BONE AND MORRIS REID, OF GLASGOW, SCOTLAND.

CHAIN-CASTING MOLD.

SPECIFICATION forming part of Letters Patent No. 736,678, dated August 18, 1903.

Application filed March 31, 1903. Serial No. 150,398. (No model.)

To all whom it may concern:

Be it known that we, JAMES BONE, merchant, and MORRIS REID, engineer, subjects of the King of Great Britain and Ireland, and 5 residents of Glasgow, Scotland, have invented certain new and useful Improvements in the Manufacture of Railway-Wagon Links, Chains, and Like Articles, of which the following is a specification, and for which a patent has been applied for in Great Britain, No. 19,129, dated the 1st day of September, 1902.

Our invention has reference to improvements in the manufacture of railway carriage 15 and wagon links, chains, chain cables, and like articles by casting same in suitable metal in a chill or metal mold-box made in two parts or plates, constructed and fitted in the manner to be described.

20 In order that others skilled in the art to which our invention relates may understand the nature of same, we have hereunto appended two sheets of illustrative drawings, in which—

25 Figure 1 illustrates a set of wagon-links of ordinary form such as may be cast at one operation according to our invention. Fig. 2 is a plan of the mold-box for the links illustrated by Fig. 1 without the counterbalancing-weights. Fig. 3 is a sectional elevation taken on the line 3 3 in Fig. 2. Fig. 4 is an inverted plan of the two upper portable blocks. Fig. 5 is a plan of the two lower portable blocks. Fig. 6 shows two half-sectional elevations at right angles to Fig. 3, the 35 left-hand section being taken on the line 6 6 and the right-hand section 7 7 both in Fig. 3. Fig. 7 is a plan, to a reduced scale, of the lower plate of the mold-box. Fig. 8 is an inverted plan, to a similar scale, of the upper plate of the mold-box. Fig. 9 illustrates a method of securing together the two plates of a mold-box which may be used for small sizes.

45 For casting a set of railway-wagon links such as are illustrated by Fig. 1 and which are made thicker at the ends to compensate for the wear at their parts a mold-box is used consisting of two plates A and B. The 50 lower plate B is supported by side standards B' and carries the guide-rod A', on which the

upper plate A slides up and down, as required, and which is counterbalanced by the weights C, suspended by the chains C', passing over the pulleys D on the shaft D', carried in the brackets E, and rotated by any suitable means, such as a crank-handle. The part A² of the guide-rod A' are formed slightly conoidal in order to effect an exact fit when the plate A is lowered onto the 60 lower plate B. The upper plate A is formed on its under surface with matrices a for one longitudinal half of each of the two end links and with a recess a³ to receive the upper pair of the portable blocks a', Figs. 3 and 6, and 65 shown in inverted plan view by Fig. 4. The lower plate B is also formed with matrices a for the other longitudinal half of the end links and a recess B² to receive the lower pair of portable blocks b. Each meeting face 70 of each pair of portable blocks a b is also formed with a matrix b' to form the mold for the center link. The upper portable blocks a are formed with three gates a³, each communicating with one of the molds for the 75 links by which the molten metal is poured. The portable blocks a' and b are also formed with matrices to complete the molds for the end links.

In casting links such as illustrated by Fig. 80 1 the upper plate A is raised by the chains C' and counterweights C to the upper end of the guide-rod A', as indicated in dotted lines in Fig. 3. The portable blocks b are placed in the cavity B² of the lower plate B, which 85 has holes formed in it to allow of dust or other matter being easily cleaned out, and the upper portable blocks a' are placed above them. The upper plate A is then lowered down onto the lower one B and the upper 90 portable blocks a', the inclined surfaces forcing the loose parts into place and making an exact fit. The molten metal is then poured by the gates a³, which project up through the upper plate A. The upper plate is then 95 raised and the portable blocks and the cast links removed and the process repeated. Small-sized mold-boxes may be simply clamped or secured together by studs F and cotter-pins F', as indicated in Fig. 9, the other arrangements being as described. In a similar manner hooks and draw-bars may be cast 100

along with the links, or the links may be cast in combination with such articles already formed.

To form chain cables or chains, the mold-boxes with portable blocks may be formed practically as described for a series of links, or sets of three links may be cast in the manner described at one operation and these sets of links be connected to one another by casting a connecting-link between each series, the formed links being inserted in the mold-box for this purpose.

Having now described our invention, what we claim as new, and desire to secure by Letters Patent, is—

1. In the casting of railway-wagon links in sets connected together, the combination in a mold-box of upper and lower plates and portable blocks substantially as set forth.
2. In the casting of railway-wagon links in sets connected together, the combination of a lower plate having a pair of portable blocks fitted in a cavity therein and formed with matrices, of an upper plate raised and lowered by chains and counterweights also formed with matrices and receiving an upper pair of portable blocks substantially as set forth.

3. In the casting of railway-wagon links in sets connected together, the combination comprising the upper and lower plates A and B 30 the portable blocks a' and b all formed with matrices, the guide-rods A' the counterweights C and chains C', substantially as set forth.

4. In the casting of railway-wagon links in sets connected together, the combination comprising the upper plate A, the upper pair of portable blocks a' , the lower plate B, the lower pair of portable blocks b substantially as set forth.

5. In the casting of railway-wagon links in 40 sets connected together, the combination with a mold-box having upper and lower plates, of the portable blocks a' and b formed with matrices on their meeting faces substantially as set forth.

In testimony whereof we have signed our names to this specification in the presence of two subscribing witnesses.

JAS. BONE.
MORRIS REID.
